SUPERHEATER WITH TEMPERATURE CONTROL

Douglas S. Carter, Scarsdale, N. Y., assignor to
The Superheater Company, New York, N. Y.

Application July 13, 1932. Serial No. 622,188

6 Claims. (Cl. 122—479)

My invention relates to superheater boilers and aims to provide an arrangement wherein the superheater normally absorbs heat at a high rate per unit area, but is protected from overheating when conditions vary from the average.

An object of my invention also is to provide a comparatively cheap arrangement of boiler and superheater adapted to deliver steam of a uniformly high temperature.

10 The novel features of my invention are pointed out in the appended claims. The invention itself, however, as well as its objects and advantages, will best be understood from the following detail description, taken in connection with the 15 accompanying drawing, of a superheater boiler arrangement in accordance with my invention selected by way of example from a number of possible embodiments thereof. In the drawing, the figure is a vertical sectional elevation through 20 a superheater boiler.

It is possible to arrange the superheater for a boiler so that the superheater may receive a large amount of radiant heat per unit of surface. Under such conditions, however, there is danger 25 of burning the elements of the superheater when conditions vary to any considerable percentage from the average. Furthermore, it is often desired to maintain the temperature of the steam at the outlet of the superheater of a boiler close 30 to a given point. Operation at a high rate of radiant heat absorption over most of its surface has usually rendered it more difficult to prevent wide variation of steam temperature. In accordance with my invention, I arrange the superheater elements so that they will operate normally 35 at a high rate of radiant heat absorption per unit area, but I protect them from overheating and also regulate the temperature of the steam at the outlet of the superheater by passing varying amounts of air in contact with elements 40 of the superheater when the conditions under which the superheater is operated depart from the normal.

In the preferred embodiment of my invention, 45 illustrated in the drawing, the superheater receives its heat largely by radiation so that the steam temperature at the outlet of the superheater tends to rise as the steam flow through the superheater decreases. The superheater surface is preferably so proportioned, however, that the desired degree of superheat is attained at the outlet of the superheater at average full load. At times of average full load, a considerable amount of air is supplied to the furnace but the 50 superheater is in no danger of overheating on

account of the cooling due to the large amount of steam. As the load drops off I employ some of the air which is introduced into the furnace to cool the superheater.

In the arrangement illustrated, boiler 10 is 60 of a well known type having a furnace chamber 12 therebelow. A burner opening 14 is shown in the front wall 16 of chamber 12 and arranged so as to deliver a flame substantially horizontally towards the rear wall 18 of the furnace. Below 65 the level of the burner aperture 14 and substantially midway of the chamber 12 is a vertical partition 20. A number of superheater elements, one of which appears at 22, are arranged intermediate the pier 20 and the rear wall 18. As 70 shown, the elements 22 are connected between a saturated header 24 and superheated steam header 26 and lie substantially horizontally so that flame from a burner in aperture 14 will pass above them and they will receive heat somewhat 75 by direct radiation from such a flame and also by radiation from the rear wall 18. The natural draft in chamber 12 being upward most of the gases from burner 14 are drawn away from the plane of the elements 22 so that such elements 80 receive very little heat by convection. However, they are sufficiently close to the flame and to wall 18 so that they receive a large amount of heat per unit area by radiation and can deliver steam of a comparatively high temperature in 85 proportion to the surface of the superheater compared to the majority of superheaters.

Air for combustion of fuel introduced through aperture 14 is supplied in part through the burner aperture itself, but a large amount of secondary air is required for insuring flame stability and complete combustion in furnace 12 and the majority of such secondary air is introduced in the arrangement shown through a duct 30 below the pier 20. Air entering through the duct 30 90 may rise and pass upwardly on either side of pier 20 depending upon the position of a damper 32 pivoted on an axis close to the lower edge of pier 20. Air passing to the left of pier 20 as shown in the figure rises through a distributing grate 100 34 immediately beneath the flame from burner aperture 14. In order to permit the entire stream of air from duct 30 to pass to the left of pier 20 the damper 32 is positioned as shown in dotted lines in the figure. The damper 32 occupies such 105 dotted line position so long as the temperature of steam in the superheated steam header 26 is not above the desired temperature. Means, however, are provided so that damper 32 is automatically swung away from the dotted line po- 110

sition as shown in the figure towards the full line position whenever the steam temperature in header 26 passes a desired point, thereby more or less closing the passage to the left of the pier 20 and opening the passage to the right of such pier so that more or less of the air from duct 30 is diverted beneath the elements 22 and rises therethrough so that it not only cools elements 22 by direct contact but also reduces the heat supply to such elements by lifting the flame farther away therefrom and also cooling the wall 18. The means illustrated for swinging damper 32 in the manner just described comprises a thermostat 36 arranged to control servo-motor 38 having a piston (not shown) therein, but the piston rod of which carries a rack 40 engaging a pinion on the shaft 42 of the damper 32 so that the damper is swung from right to left in the arrangement shown in Fig. 1 whenever conditions require that the temperature of steam in header 26 be prevented from rising further. It is clear from the drawing that when desired the entire flow of air from the duct 30 may be shifted from the left side of pier 20 to the right thereof so as to cool the elements 22 and increase the distance of the flame therefrom.

The superheater having the elements 22 being of the radiant type, it has a characteristic temperature curve rising with decrease of load. The elements 22 therefore are apt to become overheated at low loads. It is at low loads therefore that secondary air will be diverted over or through the superheater for protective uses as above described.

If desired, moreover, I may control the fuel supplied to the burner by the thermostat 36 as well as the damper for controlling the point of delivery of the secondary air. Such fuel control is not shown, however, as it forms no part of my invention.

In the arrangement shown, I have provided an opening 46 in the front wall 16 to supply a certain amount of secondary air to chamber 12 through grating 34 when the damper 32 is in its extreme left hand position. I do not limit myself to this, however.

What I claim is:

1. The combination with a boiler and a superheater therefor, of a source of heat common to both said boiler and superheater, means to supply a branched stream of air to said source for supporting combustion, said superheater lying in one branch of said stream, and means for causing the proportion of air from said stream passing over said superheater to increase as the temperature of steam from the superheater rises above a given point. 85

2. The combination with a boiler and a superheater therefor, of a burner for said boiler arranged to discharge above said superheater to heat it largely by radiation, means for passing a stream of air to the flame from said burner at a point between the burner and said superheater, and means to divert a portion of said stream thru such superheater from below upward when the temperature of steam from the superheater rises above a given point. 90

3. The combination as set forth in claim 2 and in which the superheater elements lie substantially horizontal. 95

4. The method of regulating the temperature of steam delivered by a radiant type superheater comprising burning fuel to form a flame in radiating relation to the superheater, supplying a stream of secondary air to said flame, and taking off air from said stream and passing such taken off air in such relation to said superheater as to cool it when the steam delivered thereby is above a given temperature. 100

5. The method as set forth in claim 4 and in which the air for cooling the superheater acts also to move the flame farther therefrom. 110

6. The method of regulating the temperature of steam delivered by a radiant type of superheater comprising burning fuel to form a flame in radiating relation to the superheater, supplying a stream of secondary air to said flame and taking off air from said stream and passing such air in such relation to said superheater as to cool it when the steam flow therethrough is below a given point. 115
